UNITED STATES PATENT OFFICE.

OSCAR WOODWARD, OF NEW YORK, N. Y., ASSIGNOR TO YOST WRITING MACHINE COMPANY,
OF ILION, NEW YORK, A CORPORATION OF NEW YORK.

TYPE-WRITING MACHINE.

No. 893,826.

Specification of Letters Patent.

Patented July 21, 1908.

Application filed February 16, 1907. Serial No. 357,607.

To all whom it may concern:

- Be it known that I, OSCAR WOODWARD, citizen of the United States, and resident of the borough of Manhattan, city of New York, 5 in the county of New York and State of New York, have invented certain new and useful Improvements in Type-Writing Machines, of which the following is a specification.
- 10 My invention relates to case shifting mechanism for typewriting machines and the object of said invention is to provide simple and efficient mechanism of the character specified.
- 15 To the above and other ends which will hereinafter appear, my invention consists of the features of construction, arrangements of parts and combinations of devices to be hereinafter set forth and particularly 20 pointed out in the appended claims.

In the accompanying drawings, Figure 1 is a vertical, central, front to rear sectional view of one form of typewriting machine embodying my invention, some of the parts 25 being omitted and the section being taken on the line $x-x$ of Fig. 2 and looking in the direction of the arrow at said line. Fig. 2 is a vertical transverse sectional view of the same, the section being taken on the line 30 $y-y$ of Fig. 1 and looking in the direction of the arrow at said line. Fig. 3 is an enlarged fragmentary vertical front to rear sectional view of portions of the platen shifting mechanism and associated parts, the section being 35 also taken on the line $x-x$ of Fig. 2 and looking in the direction of the arrow at said line. Fig. 4 is an enlarged fragmentary top plan view showing a portion of the platen, platen frame and carriage. Fig. 5 is a detail perspective view of a portion of the 40 platen shifting mechanism. Fig. 6 is an enlarged detail sectional view showing the pivotal connection for the rock shaft of the shifting mechanism. Fig. 7 is an enlarged 45 detail fragmentary rear elevation showing one end of the rock shaft and the associated parts.

I have shown my invention applied to a front-strike typewriting machine embodying a type action of the specific character 50 disclosed in the application of George F. Ballou, filed January 22nd, 1907, Serial No. 353,588, and of the same general character as that disclosed in the application of Arthur 55 W. Smith, Serial No. 260,441, filed May

15th, 1905, but it should be understood that the case shifting mechanism of the present invention may be employed in other styles of typewriting machines.

The frame of the machine comprises a base 60 1, corner posts 2 and a top plate 3. Key levers 4 are pivoted on a pivot rod 5 supported in rearwardly extending bracket arms 6 projecting from an auxiliary frame 7. The auxiliary frame is provided with a segment 8 to which are secured hangers 9, each hanger having a sub-lever 10 pivoted thereto at 11. A link 12 connects each key lever to the associated sub-lever. A rearwardly extending link 13 is connected at its forward 65 end to a sub-lever and at its rear end to a driver 14 pivoted at 15 to a hanger secured by screws 16 to a segment 17. Each driver is pivoted at 18 to a type bar 19 pivoted at its forward end 20 to a guide link 21. Various 70 guide links turn on a pivot wire 22 in radial guide slots 23 formed in a segment 24 carried by the auxiliary frame. A restoring spring 25 connects each driver with its associated link 13 in order to restore the parts to 75 normal position. The types 26 normally rest on the face of an inking pad 27 contained in a trough-like casing 28 detachably secured to the frame of the machine. A depression of the finger key moves the associated type 80 bar to the printing position as shown in dotted lines in Fig. 1, the lower case type following the path indicated by the dotted line a in said figure.

The frame of the machine has oppositely 85 grooved rails 29 secured thereto for co-operation with anti-friction balls or rollers 30 which likewise cooperate with oppositely grooved bars or ways 31 on a carriage truck 32. The carriage truck is provided with upwardly extending end plates 33 to which parallel guide links 34 and 35 are pivoted at 36 and 37 respectively. The forward ends of the guide links are pivoted at 38 to end plates 39 of a platen frame, said end plates being connected 90 by cross bars 40 and 41. A cross bar 42 also unites the lower set of guide links 34. Bearings are provided in the platen frame for a shaft 43 which supports a cylindrical platen 44. The cross bar 41 carries a sleeve 105 45 rigidly secured thereto about midway of its length and a depending arm 46 projects from said sleeve. An opening is formed in the lower end of the arm 46 for the reception of a hollow internally threaded spindle or 110

sleeve 47 provided with a circumferential shoulder 48 which bears against the forward face of the arm 46 as shown in Fig. 3. The forward end of the hollow spindle 47 is provided with a bearing face 49 for coöperation with a set of anti-friction balls 50. A threaded stem 51 coacts with the threads of the sleeve 47 and extends therethrough for coöperation with a nut 52 at the rear end of the stem where it projects beyond the sleeve. This nut is larger than the opening in the depending arm 46 and bears against the rear face of the arm to secure the hollow spindle and the stem 51 thereto. An enlarged head 53 is provided at the forward end of the stem 51 and the under side of this head is beveled at 54 to provide a bearing for coöperation with the set of anti-friction balls 50. The head is also provided with a slit 55 for coöperation with a screw driver or other suitable tool to facilitate an adjustment of the bearing 54 relatively to the bearing 49. The bearing faces 49 and 54 are inclined towards each other and form a race-way for coöperation with the set of anti-friction balls 50.

A roller 56 has a central opening so that it may surround the head 53 and enlarge the portion of the hollow spindle 47. This roller is also provided within the central opening 30 therein with a V-shaped groove 57 in the median plane thereof for coöperation with the set of anti-friction balls 50. By these means a ball bearing support is provided for the roller 56 and a relative adjustment 35 between the bearings 49 and 54 may be effected. The tread of the roller is grooved for coöperation with a shift rail 58 which extends throughout the width of the machine and is recessed at the opposite sides of the 40 center thereof and at different points in its length as indicated at 59 and 60. The recesses 59 and 60 are preferably near each end of the rail, the recess 60 receiving an upward projection 61 on an upright two-part 45 link 62.

Each link is provided with an off-set arm 63 which carries an upwardly projecting member 64 received in the associated recess 59 in the shift rail. Pins 65 and 66 extend 50 transversely through openings in the shift rail and in the projections 64 and 61 respectively to rigidly secure the link 62 to the shift rail at different points in the length of the latter. Each of the links 62 is preferably a two-part link united by a turn buckle 67 which coöperates with right and left-hand screw threads on the two sections of the link in order to unite them and to provide means for lengthening and shortening 60 each link at will. The upper member of each link 62 is provided with a vertical face 68, the faces 68 on the two shift links being parallel and coöperating with grooved guide rollers 69 secured by headed pivot screws 70 to lugs 71 which project upwardly from a bar

72 that extends transversely of the machine from side to side thereof and is secured at its ends by screws 73 to inwardly projecting lugs 74 on the side plates of the machine. The guide rollers 69 thus coöperate with the 70 guide links 62 to guide them in their vertical shifting movements and to maintain the shift rail against displacement from a true horizontal position. The lower end of each guide link 62 is pivoted at 75 to a rearwardly 75 extending arm 76 projecting from a shifting frame shown in detail in Fig. 5. This shifting frame comprises a rock shaft 77 flattened at 78 for coöperation with the arms 76 in order to effect a rigid connection between said 80 arms and the rock shaft. The ends of the rock shaft where they project beyond the arms 76 are recessed at 79 for the reception of pivot pins 80 (see Fig. 6) formed on the ends of set screws 81 which are received in 85 threaded openings in the base 1 of the machine and coöperate outside of the base with lock nuts 82 to secure the screws in their adjusted positions. Each of the arms 76 has a depending hook-like arm 83 to which the 90 forward end of a contractile spring 84 is secured, the rear end of said spring receiving a threaded stem 85 which is screwed into the spring and coacts with the convolutes thereof to receive an adjustment relatively to the 95 spring. The rear end of the member 85 is provided with an eye 86 which coöperates with a hook 87 received at its threaded end 88 in a tapped opening in the base 1 of the machine. By these means an adjustment 100 of the tension of each of the springs 84 may be provided. The arm 76 at the left-hand side of the machine is extended forward to form a key lever 89 provided with a finger key 90. By depressing the finger 105 key 90 the arms 76 are elevated, thereby moving the links 62 upwardly and effecting an upward movement of the shift rail carrying the platen frame through the interposed bearing roller 56 upwardly, the platen frame 110 being guided in its shifting movements by the parallel links 34 and 35. The construction is such that the springs 84 constitute 115 counterbalancing springs to take up some of the weight of the platen, platen frame and the associated parts so that comparatively slight pressure exerted upon the shift key 90 will effect an upward shift of the platen. The construction also provides efficient means for maintaining the shift rail in the 120 proper horizontal position at all times by reason of the rigid connection maintained between the links 62 and the shift rail and the coöperation of the guide rollers 69 with the shifting links; the links 62 and shift rail 125 constituting for all essential purposes a rigid frame guided by the grooved guide roller 69 and yet affording an individual adjustment at each end of the shift rail for effecting a proper adjustment thereof. Projecting out- 130

wardly from each of the end plates of the platen frame is a stop pin 91 (see Figs. 2 and 3) which is provided with a circumferential shoulder 92 that bears against the outer face 5 of the associated end plate 39 and is received in an opening 94 in an end plate of the truck and projects therethrough, the inner end portion of the pin being threaded for coöperation with a nut 93 by which the pin is rigidly 10 secured to an end plate of the platen frame. Each of these pins 91 coöperates with the screw stops 95 and 96 received in tapped openings in the top and bottom walls respectively of the opening 94 to limit the 15 shifting movements of the platen frame. Each of the screws 95 and 96 is provided with a lock nut 97 by which it is secured in its adjusted position.

What I claim as new and desire to secure 20 by Letters Patent, is:—

1. In a typewriting machine, the combination of a shiftable platen, a shift rail therefor, and a plurality of key actuated shift links each connected to the shift rail at a 25 plurality of points lengthwise of the shift rail.

2. In a typewriting machine, the combination of a shiftable platen, a shift rail therefor, a plurality of shift links each connected 30 to the shift rail at a plurality of points lengthwise of the shift rail, a key actuated rock shaft, and crank arms carried by said rock shaft and connected with said shift links.

3. In a typewriting machine, the combination of a shiftable platen, a shift rail therefor, and a plurality of key actuated shift links connected to said shift rail, each of said shift links being provided with an off-set arm that extends laterally from the link and 40 longitudinally of the shift rail, each link being secured to the shift rail at the body portion of the link and at the off-set arm thereof.

4. In a typewriting machine, the combination of a shiftable platen, a shift rail therefor, a plurality of key actuated shift links connected to said shift rail, each of said shift links being provided with an off-set arm that extends laterally from the link and longitudinally of the shift rail, each link 50 being secured to the shift rail at the body portion of the link and at the off-set arm thereof, and means for effecting an adjustment in the length of each link.

5. In a typewriting machine, the combination of a shiftable platen, a shift rail therefor, key actuated links connected with and operative to shift said shift rail, guide rollers coöperative with said links, and means for effecting an adjustment in the 60 length of each link.

6. In a front-strike typewriting machine, the combination of a vertically shiftable platen, a vertically movable shift rail therefor, vertically movable links connected with 65 and operative to shift said shift rail, a key

actuated rock shaft, crank arms carried by said rock shaft and connected with and supporting said links, and means for effecting an adjustment in the length of each link.

7. In a typewriting machine, the combination of a shiftable platen, a shift rail therefor, a plurality of shift links each connected to the shift rail at a plurality of points lengthwise of the shift rail, a key actuated rock shaft, crank arms carried by 70 said rock shaft and connected with said shift links, and means for effecting an adjustment in the length of each link.

8. In a typewriting machine, the combination of a shiftable platen, a shift rail, 80 links rigidly connected to said shift rail, a key actuated rock shaft, crank arms carried by said rock shaft and pivotally connected to said links, a second set of crank arms on said rock shaft, and springs connected to 85 said second set of crank arms.

9. In a front-strike typewriting machine, the combination of a vertically shiftable platen, a vertically shiftable shift rail, links connected to said shift rail, means for effecting an adjustment in the length of each of 90 said links, a key actuated rock shaft, crank arms carried by said rock shaft and pivotally connected to said links, a second set of crank arms on said rock shaft, springs connected to 95 said second set of crank arms, and means for effecting an adjustment of said springs.

10. In a typewriting machine, the combination of a shiftable platen, a shift rail, links rigidly connected to and operative to 100 shift said shift rail, grooved guide rollers, said links being received in the grooves in said rollers, and key actuated means for effecting a longitudinal movement of said links to shift the platen.

11. In a typewriting machine, the combination of a shiftable platen, a shift rail, links rigidly connected to said shift rail, each link having an off-set outwardly projecting arm that extends longitudinally of the shift 110 rail, means for connecting each of said links to the shift rail at different points in the length of the rail, grooved guide rollers co-operative with said links, and key actuated means for moving the links longitudinally to 115 effect a shift of the platen.

12. In a front-strike typewriting machine, the combination of a shiftable platen, a vertically movable shift rail, vertically movable links rigidly connected to said shift rail and 120 having inner parallel faces, grooved guide rollers co-operative with the inner parallel faces of said links, and key actuated means for moving said links longitudinally to shift said shift rail.

13. In a front-strike typewriting machine, the combination of a shiftable platen, a vertically movable shift rail, vertically movable links rigidly connected to said shift rail and having inner parallel faces, grooved guide 130

rollers coöoperative with the inner parallel faces of said links, a rock shaft having crank arms which are connected to the lower ends of said links, and key actuated means turning 5 said rock shaft.

14. In a front-strike typewriting machine, the combination of a shiftable platen, a vertically movable shift rail, vertically movable links rigidly connected to said shift rail and 10 having inner parallel faces, and outwardly projecting off-set arms which extend longitudinally of the shift rail and which are secured thereto, grooved guide rollers coöoperative with the inner parallel faces of said 15 links, and key actuated means for moving said links longitudinally to shift the platen.

15. In a front-strike typewriting machine, the combination of a shiftable platen, a vertically movable shift rail, vertically movable 20 links rigidly connected to said shift rail and having inner parallel faces, and outwardly projecting off-set arms which extend longitudinally of the shift rail, and which are secured thereto, grooved guide rollers coöoperative 25 with the inner parallel faces of said links, means for effecting an adjustment in the length of each of said links, a key actuated rock shaft, crank arms on said rock shaft and to which the lower ends of said 30 links are pivotally connected, a second set of crank arms on said rock shaft, springs connected to said second set of crank arms, and means for adjusting said springs.

16. In a front-strike typewriting machine, 35 the combination of a vertically shiftable

platen, a shift rail therefor, and a plurality of key actuated members projecting from said shift rail and each connected thereto at a plurality of points lengthwise of the rail.

17. In a typewriting machine, the combination of a carriage, a platen frame connected to said carriage by parallel links, a roller carried by said platen frame, a shift rail coöoperative with said roller to effect a shift of the platen frame, shift links, each 45 shift link having an off-set outwardly projecting arm that extends longitudinally of the shift rail, means for connecting each of said shift links to the shift rail at different points in the length of the rail, grooved guide 50 rollers coöoperative with said shift links, and key actuated means for moving the shift links longitudinally to effect a shift of the platen.

18. In a typewriting machine, the combination of a shift rail recessed at different points in the length thereof, shift links each having projections that take into recesses at different points in the length of the shift rail and which are firmly secured therein, and key 55 actuated means for moving said links.

Signed at the borough of Manhattan, city of New York, in the county of New York, and State of New York, this 15th day of February, A. D. 1907.

OSCAR WOODWARD.
